UNITED STATES PATENT OFFICE.

WINFRED T. POWELL, OF ROCHESTER, NEW YORK, ASSIGNOR TO THE STROMBERG-CARLSON TELEPHONE MANUFACTURING COMPANY, OF ROCHESTER, NEW YORK, A CORPORATION OF NEW YORK.

AUTOMATIC TELEPHONE SYSTEM.

Application filed March 8, 1920. Serial No. 363,971.

To all whom it may concern:

Be it known that I, WINFRED T. POWELL, a citizen of the United States, residing at Rochester, in the county of Monroe and 5 State of New York, have invented certain new and useful Improvements in Automatic Telephone Systems, of which the following is a full, clear, concise, and exact description.

10 This invention relates to telephone systems, and more particularly to telephone systems employing automatic switches in completing a telephone connection between calling and called telephone lines.

15 It is the purpose of the present invention to provide a telephone system in which the conversational circuit extends only through non-numerical switches. The various features included will appear from the detailed description and claims.

20 The drawings with Fig. 1 placed above Fig. 2 diagrammatically represent a portion of a telephone system embodying the present invention. At the upper left hand corner of Fig. 1 there is shown the operating circuits of a line or trunk selecting switch individual to a telephone line which is herein referred to as a calling subscriber's line. At the right of the dotted line 25 there is shown one trunk or link circuit with the associated operating circuits of a register sender. At the upper left hand corner of Fig. 2 there is shown the operating circuit of a link or trunk selecting switch individual to a telephone line, which is herein referred to as a called subscriber's line. At the center and at the right of Fig. 2 there is shown a group of ten relays common to the exchange, each provided with 30 ten sets of contacts. Fig. 3 indicates that both ends of each trunk or link circuit terminates in each line or trunk selecting switch. This is shown for the first four trunk or link circuits, but it will be understood that the remaining twelve contacts which bear no legends will be similarly employed as terminals for six other trunk or 35 link circuits.

The line switches and registers employed 40 in this system may be of a structure similar to that disclosed in the patent to Clement, #1,107,153, patented August 11, 1914.

As herein laid out, the present system is arranged for one hundred subscribers, each

of which is provided with an individual 55 line switch having twenty-one contacts. Since this switch is of the advance to normal type, one of these sets of contacts serves as a "home" position, while ten sets of contacts serve as terminals for the outgoing end of the ten trunk or link circuits provided; while the other ten sets of contacts serve as the incoming ends of these ten trunk or link circuits. It will be understood that the line switch is not 60 limited to the advance to normal type, but may be of the return to normal type, or may be arranged so that the line switch remains in engagement with the trunk circuit last used. Similarly the number of trunk or 65 link circuits is not limited to ten, but this number has been selected because in practice this many trunks will care for the number of simultaneous connections.

It is believed that the invention will best 70 be understood by describing the method of establishing a telephone connection from a calling substation at A to a called substation indicated at B. When the calling subscriber at A removes his receiver from its 75 switchhook (not shown), the line relay LR individual to this line is operated over a circuit extending from grounded battery, left hand winding of this relay, inner upper armature and back contact of the cut-off 80 relay CO, through the calling substation and upper-most armature and back contact of relay CO to ground. The line relay LR is energized in this circuit to attract its armatures, and at its inner armature and front 85 contact completes an operating circuit for the motor magnet MM of the line switch from ground; winding of this magnet, normally closed contact 5, armature, front contact and right hand winding of the line relay LR, armature and back contact of the motor magnet MM, and resistance to 90 grounded battery. The motor magnet MM is energized, but almost immediately interrupts its circuit to move the brushes of the 95 line switch into engagement with the set of terminals individual to the first outgoing trunk terminating at the switch. If this trunk circuit is idle, the motor magnet will be shunted, and the line relay LR will be 100 held operated and cut off relay CO energized by a circuit extending from grounded battery, resistance, back contact and armature.

105

ture of the motor magnet, right hand winding, front contact and armature of the line relay LR, upper winding of the cut-off relay CO, armature and back contact of slow releasing relay 6, trunk test brush 19, test conductor 8, back contact and armature of slow releasing relay 9, conductor 10, units register brush 11 in its normal position, conductor 12, tens register brush 13, also in its 10 normal position, back contact and armature of slow releasing relay 14, back contact and armature of impulse relay IMP to ground. As soon as the trunk is seized for use, its test circuit just described is opened by the 15 energization of the impulse relay IMP and later by the operation of the slow releasing relay 14, and subsequently when the tens and units register brushes 13 and 11 are moved from their normal position.

20 In this description it will be assumed that the first trunk circuit tested was busy, but that the second trunk circuit which is the one shown in the drawings, is idle. Under this assumption as soon as the calling line 25 switch has been moved from its normal position, a second operating circuit for the motor magnet MM of the line switch is closed from ground, winding of this magnet, off normal contact 15 now closed, innermost lower armature and back contact of the cut-off relay CO, armature and back contact of the motor magnet MM, and resistance to grounded battery. Under the control of this circuit the motor magnet advances its brushes 16, 30 17, 18, 19 and 20 into engagement with the terminals of the trunk circuit herein shown, whereupon the line relay LR is held operated and the cut-off relay CO will be energized in a circuit similar to that previously 35 described.

40 The cut-off relay when operated closes a locking circuit for itself from grounded battery, winding of relay 21, conductor 22, holding brush 18, lower winding of the cut-off relay CO, its front contact and armature, normally open contact 15, and winding of the motor magnet MM to ground. The right hand winding of the slow releasing relay 6 has an operating circuit in multiple 45 with the circuit last described, causing this relay to attract its armatures. As soon as the cut-off relay attracted its armatures, it opened the original energizing circuit of the line relay LR and closed the line circuit to brushes 16 and 17 of the line switch, whereupon a circuit is closed including both 50 windings of the impulse relay IMP in series to grounded battery. This last named relay attracts its armature, and at its front contact closes a circuit for operating the slow releasing relay 14. This relay attracts its armatures to complete an actuating circuit 55 for slow releasing relay 9 and to close break points in circuits to be described.

60 65 As soon as relay 21 attracted its arm-

tures, relay 35 was actuated in a circuit closed from grounded battery, winding of this relay, front contact and armature of relay 21, back contact and armature of relay 31 to ground. When operated, relay 35 70 closes a locking circuit for itself through the front contact and armature of relay 21, back contact and armature of relay 36, upper front contact and armature of relay 35. 75

The apparatus is now in condition to receive the impulses corresponding to the designation of the wanted subscriber's line. Let it be assumed that the number of this line is 39. The calling subscriber thereupon 80 operates his dial to transmit three impulses corresponding to the tens digit of the wanted number. In response to each of these impulses the relay IMP retracts its armature. At the first retraction 85 of its armature a circuit is closed from ground, armature and back contact of this relay, inner armature and front contact of relay 14, winding of the slow releasing relay 23 to grounded battery and the relay 23 90 actuates its armatures. A circuit in multiple with that last described is simultaneously closed from grounded battery, winding of the motor magnet 24, armature and back contact of the switching relay 25, left 95 hand front contact and armature of relay 14, and back contact and armature of relay IMP to ground. In response to each of these tens impulses the motor magnet 24 of the tens register operates its brushes 13 and 100 26 (Fig. 2) until the brush 13 is in engagement with contact 27, and the tens register brush 26 is in engagement with contact 28. At the close of this series of impulses, the 105 relay IMP attracts its armature for a relatively long interval, and at its back contact and armature opens the energizing circuit for the slow releasing relay 23 for a long enough period so that this relay retracts its armatures. At the outer armature and back contact of relay 23 a circuit is closed from 110 ground, continuity spring 29, winding of switching relay 25, brush 13, contact 27, back contact, armature and winding of the motor magnet 24 to grounded battery. The 115 motor magnet 24 does not operate in series with the relay 25, but the relay 25 is actuated and closes a locking circuit for itself from ground, through its armature and continuity spring to grounded battery at the 120 magnet 24.

The calling subscriber thereupon transmits 9 impulses corresponding to the units digit of the wanted number whereupon the 125 impulse relay IMP again vibrates its armatures to effect the energization of the relay 23, but now these impulses are repeated to the motor magnet 30 of the units register. The operating circuit of this last named motor magnet extends from grounded bat. 130

tery, its winding, back contact and armature of relay 31, left hand front contact and armature of relay 25, front contact and armature of slow releasing relay 14, and back contact and armature of relay IMP to ground. At each retraction of the relay IMP, the motor magnet 30 of the units register advances the brushes 11 and 32. In response to the 9 impulses transmitted, 10 these brushes will be in engagement with contacts 33 and 34 respectively.

At the close of the units series of impulses, the relay IMP again attracts its armatures to interrupt the operating circuit 15 of the slow releasing relay 23, and this relay de-energizes to close a circuit from ground, its armature and back contact, winding of relay 31, units register brush 11, contact 33 with which it is now in engagement, 20 armature, back contact and winding of the motor magnet 30 to grounded battery. The motor magnet 30 does not energize in series with the relay 31, but the relay 31 is operated and closes a locking circuit for itself from 25 ground, through its inner right hand armature and front contact to grounded battery at motor magnet 30. With relays 31 and 35 operated and with the extended starter wire in the condition shown in Fig. 1, relay 36 30 will be operated to initiate the operation of the called line switch. Relay 36 is actuated in a circuit traceable from grounded battery, winding of this relay, lower-most front contact and armature of relay 35, outer- 35 most armature and continuity spring of relay 31 to the back contacts and armatures of relay 37 to ground. Relay 36 attracts its armatures and at its left hand armature and back contact opens the locking circuit 40 of relay 35, while at its inner right hand front contact and armature a circuit is closed from ground over conductor 37, brush 26, contact 28 of the tens register, winding of relay 39 to grounded battery. 45 The relay 39 attracts its armatures and closes its ten sets of contacts.

It will be first assumed that the wanted line is idle under which assumption a circuit 50 will be closed from ground, outer-most right hand armature and front contact of relay 36, conductor 40, right hand winding of relay 38, brush 32 and contact 34 of the units register, conductor 41, lower-most armature and back contact of the cut-off relay CO' of the called 55 line, and left hand winding of relay 42 to grounded battery. The relay 42 attracts its armatures and at its inner left hand armature and front contact closes a circuit from grounded battery, left hand winding 60 of the line relay LR, conductor 43 to ground over conductor 41 as previously described.

As soon as line relay LR' of the called 65 line attracts its armatures it closes a locking circuit for itself from grounded battery, its left hand winding, inner left hand arma-

ture and front contact of relay 42, lower-most armature and back contacts of relay CO', outer-most left hand armature and contact of relay 42, outer front contact and armature of relay LR' to ground. The relay 42 is held energized in a circuit in multiple of that last described including its left hand winding. Also when the line relay LR' of the called line attracts its armature, an operating circuit is closed for the motor 70 magnet 44 of the called line switch from ground, winding of this magnet, normally closed contact 45, inner right hand armature and front contact and winding of line relay LR', armature and back contact of motor magnet 44, and resistance to grounded battery. Under the control of this circuit the motor magnet 44 moves its brushes 46, 47, 48, 49 and 50 into engagement with the terminals corresponding to the first trunk terminating at the called line switch. If this trunk circuit is the one that has been seized by the calling line switch, the motor magnet 44 will cease to be actuated otherwise it will be operated in a circuit traceable from 75 ground, winding of this magnet, normally open contact 46, inner-most lower contact and armature of relay CO', armature and back contact of motor magnet 44 and resistance to grounded battery. Since the relay 42 is operated at this time, test brush 50 instead of the test brush 49 is now effective to 80 hunt for the trunk or link circuit seized by the calling line switch. As soon as the contacts of this trunk circuit are reached, a circuit will be closed from ground, outer-most left hand front contact and armature of relay 38, conductor 51, test brush 50, right hand front contact and armature of relay 42, upper winding of cut-off relay CO', inner 85 right hand armature, front contact and winding of line relay LR', armature and back contact of motor magnet 44, and resistance to grounded battery. The cut-off relay CO' attracts its armatures and at its 90 inner-most lower armature and back contact opens up the operating circuit of the motor magnet 44, while at the upper armatures and back contacts of this relay the energizing circuit of the line relay LR' which 95 is effective on the initiation of a call, is opened and at the upper armatures and front contacts of this relay the called line is extended to the line switch brushes 46 and 47 now in engagement with the seized trunk 100 circuit. At the inner lower armature and front contact of the cut-off relay CO' a locking circuit is closed from ground, winding of the motor magnet 44, contact 46, armature, front contact and lower winding of 105 cut-off relay CO', holding brush 48, conductor 52, armature and front contact of relay 9, now energized, winding of relay 53 to grounded battery. A circuit in multiple 110 with that just described includes the right 115

hand winding of relay 42 so that relay 42 is also held energized. As soon as the relay 53 attracts its armatures the locking circuit of relay 38 is opened and this relay de-energizes, while at the left hand armature and front contact of relay 53 a circuit is closed from ground, armature and back contact of battery feed relay 54, armature and front contact of relay 53, winding of the ringing relay RING and resistance to grounded battery. The ringing relay attracts its armatures to close a ringing circuit to the called line extending from the ringing machine generally designated 55, right hand winding of the trip relay TRIP, left hand front contact and armature of ringing relay RING, conductor 56, line switch brush 47, innermost upper front contact and armature of cut-off relay CO', through the substation circuit and bell of the called subscriber, uppermost armature and front contact of cut-off relay CO', line switch brush 46, conductor 57, resistance 59, right hand armature and front contact of relay RING, inner right hand armature and front contact of relay 53, and outer left hand armature and front contact of relay 14 to ground. The low resistance 59 causes a ringing tone to be heard in the receiver at the calling substation, so that the calling subscriber knows that ringing current has been applied. When the wanted subscriber answers by removing his receiver from its switchhook, the trip relay attracts its armatures and short circuits relay RING. This relay then releases and closes a locking circuit for relay TRIP, and completes an energizing circuit for relay 54. This locking circuit for the trip relay is closed from grounded battery, its left hand winding, armature and front contact, right hand back contact and armature of the ringing relay, right hand front contact and armature of relay 53, conductor 60, outer front contact and armature of the slow releasing relay 14 to ground. As soon as the battery feed relay 54 attracted its armature, it closed a substitute holding circuit for the slow releasing relay 9 which controls the release of the called line switch. It will now be assumed that when the relay 36 was energized after the setting of the tens and units register the wanted line was busy. Under this condition when ground is extended over conductor 41 to the called line switch, this circuit will be opened at the lower-most armature and back contacts of the cut-off relay CO'. Therefore the line relay LR' and the slow releasing relay 42 will not be actuated and the called line switch will not be operated. Therefore relay 53 will not attract its armatures, so that a circuit will be completed to the calling line to transmit a busy tone from the busy machine EZ, left hand armature and

front contact of relay 21, inner lower back contact and armature of relay 35, conductor 61, middle back contact and armature of relay 38, outer back contact and armature of relay 53, conductors 58 and 62 to the calling line, conductor 63, right hand winding of relay IMP to ground. When the calling subscriber receives this busy signal he replaces his receiver on its switchhook to cause the release of his line switch.

In the present arrangement, the calling subscriber controls the release of his line switch while the called subscriber's line switch is under his control. When the calling subscriber replaces his receiver on its switch hook relay IMP de-energizes and a circuit is closed from ground, armature and back contact of relay IMP, inner armature and front contact of relay 14 still energized, winding of slow releasing relay 23 to grounded battery. Relay 23 attracts its armatures and shortly afterward relay 14 de-energizes, but a circuit is momentarily closed from ground, right hand armature and back contact of relay 14, inner armature and front contact of relay 23, conductor 22 to short circuit the cut-off relay CO and the relay 6, causing them to retract their armatures, but relay 21 is held operated. After a very short interval the relay 23 retracts its armatures restoring relay 21. When relay CO retracts its armatures an operating circuit is closed for the motor magnet MM of the calling line switch extending from ground, winding of this magnet, contact 15, inner lower armature and back contact of cut-off relay CO, armature and back contact of the motor magnet MM and resistance to grounded battery. Under the control of this circuit the motor magnet advances its brushes by interrupting its own circuit until the home position of the line switch is reached, at which time contact 15 will be opened and contact 5 closed.

When the called subscriber replaces his receiver on its switchhook, the battery feed relay 54 de-energizes and opens the operating circuit of the slow releasing relay 9. After a short interval, relay 9 deenergizes and opens the holding circuit for relays 53, CO' and 42, causing these relays to retract their armatures. At the inner lower armature and back contact of cut-off relay CO' an operating circuit is closed for the motor magnet 44 of the called line switch, which circuit extends from ground, winding of the motor magnet, normally open contact 46, armature and back contact of relay CO', armature and back contact of the motor magnet 44, and resistance to grounded battery. The motor magnet by interrupting its own circuit advances the brushes of the line switch to their normal position at which time the contact 46 is opened and contact 45

closed, thus leaving the called line switch and its circuits in condition for use on a succeeding call.

Let it be assumed that B desires to call A and that the designation of A's line is #26. Under this assumption when B removes his receiver from its switchhook, his line switch will now advance to the outgoing end of an idle trunk instead of to the incoming end of such a trunk circuit as in the case when his line was that called. After the seizure of an idle trunk circuit, B will then operate his dial first, to send two impulses to set the tens register and thereafter six impulses to set the units register. After these operations when the relay corresponding to 36 of Fig. 1 is actuated to effect the completion of a call, relay 70 instead of 39 will be operated and ground will be extended over conductor 40 through the right hand winding of a relay similar to 38, to a units brush similar to 32 now in engagement with its contact 71, contact 72 of the relay 70, conductor 73, lowermost armature and back contact of relay CO, left hand winding of relay 6 to grounded battery. Relay 6 attracts its armatures and thereby closes an operating circuit for the line relay LR from grounded battery, left hand winding of this relay, inner left hand armature and front contact of relay 6 to ground at the outer right hand armature and front contact of relay 36, over conductor 73. The relays LR and 6 are locked operated and the motor magnet MM of the line switch individual to A's line will operate to seize the incoming end of the trunk circuit which has been seized by the line switch individual to B's line. Thereafter the ringing and releasing operations will take place in the manner previously described.

In accordance with another feature of this invention if it is desired to provide several substations having the same designation for the use of any subscriber, means are provided to automatically connect a calling subscriber with some one of these substations as long as any one of them is idle. To accomplish this result conductors shown at 75 of Fig. 1 and 76 shown at Fig. 2 are employed. Let it be assumed that the subscriber A is provided with two or more substation sets, and let it further be assumed that when A was called his first substation was busy in which case the cut-off relay CO will have its armatures attracted, so that when conductor 73 is extended to the first substation circuit individual to A, it will be further extended over conductor 75 to a second line switch circuit and telephone substation identical with that shown in the upper left hand corner of Fig. 1. The operation of this second line switch will be similar to the operation of the other line switches in seizing the incoming end of a trunk circuit that is

being extended to the substation. It will of course be understood that by the use of one or more conductors similar to 75, one or more telephone lines with an individual line switch for each line may be provided for each subscriber's use, or if it is desired only one line will be provided for the use of each subscriber in which case conductors 75 and 76 will be omitted.

In the early part of this description reference was made to an extended starter wire circuit. This circuit functions to effect the connection of telephone lines, one at a time, after the restoring of the wanted numbers on the register senders. 75

By reference to Fig. 1 it will be noted that the starter wire extends from ground at the armatures and back contacts of relay 37, which is common to all the register senders, over conductor 80, continuity spring and contact 81 of relay 31, conductor 82 and through the continuity springs and contacts similar to 81 of relays similar to 31, through the series of register senders. It will thus be seen that whenever a relay 31 of any of the senders is operated, it interrupts the starter wire to succeeding senders in the series at this contact 81. A further description of the starter wire is not believed to be necessary since the use of such an arrangement for other purposes has been previously used in this art. 80 85 90 95

In the present system the circuits have been so arranged that when either party abandons the connection a busy tone will be transmitted to the party maintaining the connection to indicate that the connection is now incomplete. The circuit for transmitting this tone to the calling party is identical with that employed in transmitting the busy tone to this party when the called subscriber is busy. The circuit for transmitting this tone to the called party extends from the busy machine, armature and back contact of relay 21, conductor 84, outer right hand front contact and armature of relay 53, conductors 58 and 57 to the called substation, conductor 56, armature and back contact of ringing relay RING, and right hand winding of relay 54 to grounded battery. 100 105 110 115

What I claim is:—

1. In a telephone system, a plurality of telephone lines, a trunk selecting switch for each of said lines, a trunk circuit common to said lines, a sender individual to said trunk, said sender including rotary register switches arranged to be variably adjusted from a distant point, means for causing each trunk selecting switch to seize one end of said trunk when its associated line originates a call, and means including said sender for causing each of said trunk selecting switches to seize the other end of said trunk circuit when its associated line is called. 120 125

2. In a telephone system, a plurality of 130

telephone lines, a trunk selecting switch individual to each of said lines, a plurality of trunk circuits common to said telephone lines, each of said trunk circuits being provided with a sender, both ends of each trunk circuit terminating in each trunk selecting switch, and means including a sender for actuating a trunk selecting switch to seize a trunk circuit in completing a telephone call, 10 said sender including register switches arranged to be variably adjusted from a distant point.

3. In a telephone system, a plurality of telephone lines, a trunk selecting switch individual to each of said lines, a plurality of trunk circuits, each trunk selecting switch having fixed contacts in which said trunk circuits terminate and movable contacts in which a telephone line terminates, a sender 15 individual to each trunk circuit, each trunk circuit having its ends conductively separated but inductively connected together, the ends of each of said trunk circuits terminating in each of said trunk selecting switches, 20 and means including a sender for operating a trunk selecting switch in completing a call.

4. In a telephone system, a telephone line, a trunk selecting switch individual to said line, a trunk circuit terminating at two points in said switch, a sender individual to said trunk circuit, said sender including a plurality of register switches arranged to be variably adjusted from a distant point and 30 arranged to be restored to a definite normal position when not in use, means for advancing said trunk selecting switch to one point when said line originates a call, and means including said sender for advancing said 35 trunk selecting switch to the other point when said telephone line receives a call.

5. In a telephone system, a plurality of telephone lines, a trunk selecting switch for each of said lines, each trunk selecting switch having fixed contacts and co-operating movable contacts in which a telephone line terminates, a plurality of trunk circuits terminating in the fixed contacts of said trunk selecting switches, a sender individual 45 to each trunk circuit for storing up the designation of wanted lines, said sender including a plurality of register switches, means for variably setting said sender in response to impulses transmitted over a telephone line, and means operative in response to the setting of said sender for causing the trunk selecting switch of the wanted line to complete the connection.

6. In a telephone system, a plurality of telephone lines, a trunk selecting switch individual to each of said lines, a plurality of trunk circuits terminating in each of said trunk selecting switches, a register sender individual to each trunk circuit, means for 60 variably setting said sender in response to

impulses transmitted over a telephone line, a group of relays having a set of contacts for each of said telephone lines, and means controlled by said register sender and said group of relays for causing the trunk selecting switch of the wanted telephone line to complete the connection. 70

7. In a telephone system, a plurality of telephone lines, a trunk selecting switch for each of said lines, a plurality of trunk circuits each provided with a sender, each register sender including a plurality of progressively movable switches arranged to be variably adjusted in succession from a distant point, both ends of each of said trunk 75 circuits terminating in each of said trunk selecting switches, and means controlled by a sender for causing two trunk selecting switches to seize a trunk in completing a connection between two telephone lines. 85

8. In a telephone system, a plurality of lines, a progressively movable rotary line switch for each of said lines, a plurality of trunk circuits each provided with a register sender, each register sender including a plurality of step by step switches of the advance to normal type, both ends of each of said circuits terminating in each of said switches, and means controlled by a register sender to operate two rotary line switches 90 to seize a trunk circuit in completing a connection between two telephone lines.

9. In a telephone system, a calling telephone line, a called telephone line, an individual trunk selecting switch for each of said lines, trunk circuits for said switches, a register sender individual to each trunk circuit, and means including a register sender by which the calling subscriber initiates the operation of the individual switch of the called line to establish a talking connection between the two lines, said register sender having a step by step switch for each digit of the designation of called lines. 100 105

10. A telephone system comprising means for automatically trunking calling subscribers' lines into connection with the lines of the called subscribers, said means including an individual trunk selecting switch for each of said subscribers' lines, trunk circuits 110 for said switches, and a register sender individual to each trunk circuit controlled by the calling subscriber by which the individual trunk selecting switch of any called subscriber is operated to complete the trunking connection thereto, each register sender having a plurality of step by step rotary switches 115 and operating circuits therefor. 120

11. A telephone system comprising subscribers' lines, an individual trunking switch for each of said lines, trunk circuits to be seized by said trunking switches, a register sender individual to each trunk circuit, a calling subscriber - controlled automatic means including a sender for causing the 125 130

operation of the individual trunk selecting switch of the called line to complete a connection thereto, each sender having a plurality of step by step register switches and 5 means for restoring said switches to normal on the abandonment of a call.

12. A telephone system comprising subscribers' lines, a plurality of trunk circuits, an individual switch for each line and functioning to seize idle trunk circuits, a sender individual to each trunk, each sender including a plurality of rotary step by step switches of the advance to normal type, and means controlled by the calling subscriber 15 by way of a sender for automatically operating the called switch for completing the connection to the called line.

13. A telephone system comprising subscribers' lines, a plurality of trunk circuits, 20 switches each having fixed contacts and movable contacts connected to a telephone line cooperating with said fixed contacts, trunk circuits terminating in said fixed contacts, operating means for each line switch for connecting a telephone line to a trunk circuit, a sender individual to each trunk, each sender including a plurality of step by step register switches for storing the several 25 portions of the designation of the called lines, means controlled over a calling line for variably adjusting a plurality of switches of 30 a register sender, starting circuits for said telephone lines, a plurality of relays for said telephone lines, each relay being common 35 to a different group of lines, means including one of the register switches of a selected sender for actuating the relay common to the group of lines containing the calling line to close a break-point in the starting 40 circuit for said called line and means including a second register switch for closing a second break-point in said starting circuit whereby the switch of the called line is set in 45 operation to connect said called line to the selected trunk circuit.

14. In a telephone system, a plurality of telephone lines, a plurality of trunk circuits, individual switches for extending said lines to idle trunks, each switch including fixed 50 contacts serving as terminals for the trunk circuits, movable contacts for a telephone line and co-operating with said fixed contacts, separate operating means for each line switch, a register sender individual to each 55 trunk circuit, each register sender including a plurality of switches arranged to be variably adjusted in succession over the calling line to store the indication of a called telephone line, a plurality of starting circuits 60 for setting in operation an individual switch which functions to connect called lines to selected trunks, a group of relays common to said lines and provided with a set of contacts for each telephone line and means

including one of said register switches for 65 actuating the contacts of one of said relays, the starting circuit of the called line being completed through contacts of the actuated relay and through the other switch of the register sender. 70

15. In a telephone system, a plurality of telephone lines, a plurality of trunk circuits, trunk selecting switches for connecting calling telephone lines to idle trunk circuits, each trunk circuit being provided with a 75 register sender having a plurality of switches for storing the designation of a wanted telephone line, means responsive to the initiation of a call on one of said lines for operating a trunk selecting switch to seize 80 an idle trunk circuit and its associated register sender, means controlled over said calling line for variably operating the selected register sender in accordance with the indication of a wanted telephone line, a 85 plurality of starting circuits one for each telephone line, a group of relays common to said telephone lines having contacts controlling break-points in said starting circuits, means including one of the switches 90 of the selected register sender for actuating some one of said relays to close a break-point in a starting circuit and means including the other register switch of the selected register sender to complete said starting circuit 95 for causing a trunk selecting switch to extend the called line to the selected trunk circuit.

16. In a telephone system, a plurality of telephone lines, a plurality of trunk circuits, 100 trunk selecting switches for connecting calling telephone lines to selected idle trunk circuits, each trunk circuit being provided with a register sender having a plurality of switches for storing the designation of 105 wanted telephone lines, means responsive to the initiation of a call on one of said lines for operating a trunk selecting switch to seize an idle trunk circuit and its associated register sender, means controlled over said 110 calling line for variably operating the selected register sender in accordance with the indication of a wanted telephone line, a plurality of starting circuits one for each telephone line, a group of relays common to said 115 telephone lines and having contacts controlling break-points in said starting circuits, means including one of the switches of the selected register sender for actuating some one of said relays to close a break-point in a starting circuit and means including the other register switch of the selected register sender to complete said starting circuit 120 for causing a trunk selecting switch to extend the called line to the selected trunk 125 circuit, means for disabling the starting circuit of a busy called line and means responsive to the failure of the completion of the

starting circuit for applying a busy signal to the calling telephone line.

17. In a telephone system, telephone lines, several of said telephone lines being assigned to the use of one subscriber, a plurality of trunk circuits, trunk selecting switches for extending telephone lines to selected idle trunk circuits on the initiation of a call, a register sender associated with each trunk circuit, said register sender including a plurality of register switches for storing the designation of called telephone lines, means for rendering telephone lines busy, means responsive to said register sender for causing a trunk selecting switch to extend the called line to the selected trunk circuit and means for extending a second telephone line assigned to the called subscriber to the selected trunk when the first line of the subscriber is busy and means for signalling the called telephone line.

18. In a telephone system, telephone lines,

several of said telephone lines being assigned to the use of one subscriber, a plurality of trunk circuits, trunk selecting switches for extending telephone lines to selected idle trunk circuits on the initiation of a call, a register sender including a plurality of register switches for storing the designation of called telephone lines, means for rendering telephone lines busy, means responsive to said register sender for causing a trunk selecting switch to extend the called line to the selected trunk circuit, and means for extending a second telephone line assigned to the called subscriber to the selected trunk when the first line of the subscriber is busy and means for signalling the called telephone line.

In witness whereof, I hereunto subscribe my name this 23rd day of February, A. D. 1920.

WINFRED T. POWELL.
